SLIDER MECHANISM

Oscar Frégeolle, Central Falls, R. I., assignor to
 Hemphill Company, Central Falls, R. I., a corporation of Massachusetts

Application February 1, 1946, Serial No. 644,786

2 Claims. (Cl. 66—14)

1

This invention relates to a new and useful improvement in circular, independent needle, knitting machines having superposed axially aligned cylinders equipped with double ended needles adapted to knit in either cylinder. In machines of this type, the needles are usually operated by sliders in the slots of each cylinder which can be coupled to and uncoupled from needles as required. Normally, the shanks of such sliders with the exception of their operating butts are of a uniform width slightly less than the depth of the cylinder slots and are retained therein by one or more spiral spring bands fitting closely around the cylinder.

When transferring from rib to plain knitting or from one type of rib to another type it is usually necessary to transfer needles from the upper to the lower cylinder and, consequently, to uncouple them from the upper cylinder sliders so that they can operate in the lower cylinder. Such uncoupling is effected by swinging the lower end of each upper cylinder slider concerned outwardly so that its hook is separated from the upper hook of the corresponding needle. This brings the lower end of the slider completely outside the upper cylinder walls and practically its entire length projects to some extent. In consequence, the resilient retaining bands are sprung outwardly adjacent the transfer point and, since the sliders are progressively uncoupled, the bands are held out more or less constantly so that they are incapable of returning a slider which has completed this transfer back into its cylinder slot with the necessary speed. The primary object of this invention is to eliminate this difficulty and to insure that each slider involved in a transfer is returned quickly to its normal position within a cylinder slot.

One form of the invention is shown in the drawings of which:

Figs. 1, 2 and 3 are diagrammatic enlargements of three upper cylinder sliders swung outward to the extreme transfer position;

Figs. 4, 5 and 6 are similar views of the same sliders in retracted position immediately after transfer;

Fig. 7 is a plan view largely in section illustrating the way in which a slider of this invention may be swung out for transfer without disturbing the control of at least one of the retaining bands;

Figs. 8 and 9 are side elevations, viewed from outside and inside respectively, of the retaining bands and the means for maintaining them in their proper positions with respect to the cylinder; and

2

Fig. 10 is a view illustrating prior practice.

The condition prevalent when ordinary sliders having shanks of uniform width are used is diagrammatically shown in Fig. 10, in which slider 1 is assumed to be in the same position as the sliders shown in Figs. 1, 2 and 3, i. e., in its extreme downward and outward transfer position. By it, retaining band 2 has been sprung out as shown. Slider 3 which preceded slider 1 through the transfer operation should have returned by this time to completely within its cylinder slot but instead follows the curve of the outsprung band 2 as shown. This is true even of sliders preceding slider 3. If as is frequently the case, the transfer point is close to the point at which yarn is fed, a slider in this position will strike the yarn feed or other parts of the machine with resulting damage. By this invention, this condition cannot occur since each slider is returned to its slot practically instantaneously after transfer by a band the operation of which is unaffected by any other preceding or subsequent slider.

In Figs. 1-6 the upper cylinder is shown at 4. It has the usual walls 5 forming slots within which the needles and sliders operate. In Figs. 1-3 three sliders 6, 7 and 8 are shown in the extreme downward and outward position assumed when their needles are transferred from the upper to the lower cylinder. This transfer may be effected by needle divider 9 such as that disclosed in application for U. S. Letters Patent Serial No. 559,136 filed October 18, 1944. The upper cylinder is surrounded by three slider retaining spring bands 10, 11 and 12. Slider 6, instead of being of uniform width throughout the length of its shank as is usual, is provided with two recesses 13 and 14 so positioned and proportioned that bands 10 and 12 will not be displaced when band 11 is swung out by the outward swinging of slider 6 during transfer as shown in Fig. 1.

Therefore, slider 6 will be returned to its normal position within the cylinder slot, at the earliest permitted instant, by band 11 the action of which is not influenced by any other slider. Slider 7 is provided with a single recess 15 so proportioned and positioned that when it is swung out into the extreme transfer position shown in Fig. 2 it will carry its band 10 with it but will leave bands 11 and 12 undisturbed. Similarly, when slider 8 is swung out to the same transfer position by needle divider 9 as shown in Fig. 3 it carries band 12 with it but does not disturb bands 10 or 11 because of recess 16 which is suitably proportioned and positioned for this result. That is to say, each slider during transfer is

under compression from its own retaining band and the outward springing of this band has no effect whatever upon the positions or conditions of the similar bands associated with the other sliders. Therefore, the return of each slider to its slot after transfer will not be retarded by the fact that its band is being held out by a subsequent slider going through the transfer operation.

In Figs. 4, 5 and 6 it is assumed that the same sliders 6, 7 and 8 have completed the transfer and have been returned within their cylinder slots. It will be noted that slider 6 is still under the control of band 11, slider 7 of band 10 and slider 8 of band 12 each of which engages a part of the slider of normal width. Even though two of the bands may be opposed to a recess or recesses in a slider the remaining band maintains the control. If the sliders are moved further upward in their slots which, of course, happens during the knitting operations, it will be obvious that one or more of the bands 10, 11 and 12 will be opposed to some part of each slider of normal width and will, consequently, oppose any tendency of the slider to move out of its slot. No slider is ever free of this control.

In Fig. 7, it is assumed that 1x1 rib knitting has been in process and that, in consequence, alternate sliders are to be transferred to the lower cylinder for the production of a plain leg. In this figure, slider 7 is in the extreme outward transfer position as shown in Fig. 2 and retaining band 10 is in the corresponding outwardly sprung position also as shown in Fig. 2. Slider 8, which has just completed transfer, has been fully restored to its slot already by its band 12 which is unaffected by the outswinging of slider 7.

It will be noted that in Fig. 7 sliders 7 and 8 are spaced apart by another slider or cylinder slot. This is because of the assumption the machine had been knitting 1x1 rib fabric prior to transfer. If it had been knitting 6x3 rib sliders 6, 7 and 8 would, of course, follow one another directly. If a rib panel more than three needles in width is knit before transfer so that groups of more than three needles have to be transferred, the sequence of sliders 6, 7 and 8 can be repeated in whole or in part with respect to the additional needles and control of all of them maintained, as above described, by the same three bands 10, 11 and 12. However, the invention is not limited to sliders or bands in sets of three but includes any number of sliders and any number of bands required to effect the mode of operation above described, the slider recesses being positioned and proportioned and the bands being sufficient in number so that at all times at least one band will return a single slider to its slot immediately after transfer without influence by or upon any sliders which may be going through the transfer operation.

Because of the passage of the slider recesses

across the bands there is a possibility that the bands may be vertically displaced. To prevent this, the retainer shown in Figs. 8 and 9 may be provided. As shown, this consists of a bracket 17 attached to any suitable fixed part of the machine and which supports a U shaped retainer 18 provided with inwardly projecting slots 19, 20 and 21 through which bands 10, 11 and 12 pass. Retainer 18 straddles the point at which transfer occurs and thus holds the three bands in correct vertical position at either side of the point at which correct placement of the bands is essential. It is adjustable vertically as indicated by slots 22 and screws 23.

This invention may also be used upon eccentric and concentric wrap spindles of the type employing swingable fingers to insure the prompt return of the fingers to their idle position inside of the needle circle. By recessing the fingers in a manner similar to that shown herein for sliders, the independent return of each finger by its own band can be assured. The invention may be used for still other purposes which without further disclosure will occur to those skilled in the art as occasion arises.

I claim:

1. For a circular, independent needle, knitting machine having coaxial cylinders provided with needle slots, the combination of identical groups of sliders within the slots and each slider being adapted to move longitudinally thereof and to be swung outwardly thereof, a plurality of resilient means surrounding said cylinder for maintaining said sliders within their slots regardless of their longitudinal position, means for swinging the lower end of each slider outwardly from its slot adjacent the lower end of its longitudinal travel, each of said sliders being provided with one or more depressions in its outer edge so positioned that each slider will have operative contact with only a single one of said resilient means when outswung.

2. For a circular, independent needle, knitting machine having coaxial cylinders provided with needle slots, the combination of identical groups of sliders within the slots and each slider being adapted to move longitudinally thereof and to be swung outwardly thereof, a plurality of resilient means surrounding said cylinder for maintaining said sliders within their slots regardless of their longitudinal position, means for swinging the lower end of each slider outwardly from its slot adjacent the lower end of its longitudinal travel, each of said sliders being provided with one or more depressions in its outer edge so positioned that each slider will have operative contact with only a single one of said resilient means when outswung and means for retaining said plurality of resilient means in predetermined, spaced, longitudinal positions around said cylinder.

OSCAR FREGEOLLE
